GUY M. PETERSON, OF SPRINGFIELD, MASSACHUSETTS, ASSIGNOR TO CHENEY BIGELOW
WIRE WORKS, OF SPRINGFIELD, MASSACHUSETTS, A CORPORATION OF MASSACHU-
SETTS

FOURDRINIER WIRE FABRIC

Application filed September 4, 1930. Serial No. 479,733.

This invention relates to an improved paper making wire fabric such as is used in Fourdrinier machines, and has for its object the production of a stronger and more durable 5 fabric without materially increasing the cost and in no way changing or destroying the requisite characteristics of such a fabric for paper making purposes.

At the present time Fourdrinier fabric is 10 usually made up of interwoven fine wires of copper or its alloys, bronze and brass, which metal is relatively soft and of small tensile strength. In a paper making machine the soft wire wears down rapidly and this wear 15 is materially increased by the stretching or lengthening of the fabric, which is considerable because of its weak tensile strength. The use of such a fabric therefore requires a frequent taking up of the slack due to stretch 20 and eventual replacement after a short period of time.

The purpose of my improvement is to 25 lengthen the life of the fabric both by decreasing its stretch and increasing its wear, and in carrying out this object I have introduced into the warp of the fabric which carries the more severe longitudinal strain when in use, interspersed warp wires of stainless steel preferably at regularly spaced intervals 30 throughout the width of the fabric. The main body of the fabric may be constituted as at present, of coppery wires both as to the weft and remaining warp wires, the invention being in the substitution for every 35 alternate coppery warp, or for every third, fourth, fifth, etc. coppery warp and as few as for one in twenty of the coppery warp, of a warp of stainless steel or equivalent metal which is harder, more durable and of 40 considerably greater tensile strength than bronze, brass or copper wires while being of an equally rustless character therewith. The substituted warp of stainless steel may be of the same size as its displaced coppery warp 45 and in all other respects the characteristics of the wire fabric, as to mesh, size of wires, etc. may conform to standard practice so that its paper making characteristics may remain unchanged and suit the various purposes desired for such fabric.

In the accompanying drawing I have illustrated a section of Fourdrinier fabric greatly enlarged to show a preferred embodiment of the invention.

In this figure "a" indicates the coppery 55 warp wires, "b" the coppery weft wires and "c" the interspersed warps of stainless steel. In the embodiment shown, the wires are all of the same size, the warp and weft wires are 60 equally spaced and are interwoven with a plain weave. It will be understood however, that variations in size and spacing of the wires and character of the weave may be resort to and still retain the improved results of my invention.

It will be noted also in the embodiment illustrated, that the stainless steel warp wires 65 c are inserted at intervals of every seventh warp, which has been found to be a suitable average spacing for a Fourdrinier fabric of 70 medium mesh and size of wire. In an actual fabric this spacing between the steel warp wires will be approximately 5/32 of an inch. There has been no attempt to show the drawing in scale. In many cases, it may be found 75 desirable to change the spacing of the steel wires from the precise form shown and described, and particularly for increasing the longitudinal strength at the selvage, the steel wires may be more closely spaced than as here 80 shown.

The advantages flowing from the present improvement are manifold, the principal ones being that of greater tensile strength and 85 wearing quality as previously indicated. The harder, more durable steel wire assumes the greater burden of wear on the rolls when the fabric is in use, even though said steel wires may be of no greater size and therefore do not project from the surface of the fabric. Furthermore, the stretching of the fabric is 90 greatly reduced by the use of the interspersed steel wires and the coppery wires are thus kept from being drawn out, which would shorten their wearing life. Moreover, when 95 the steel wires eventually weaken, usually due to a gradual hardening of the metal from repeated bending, the coppery wires in the main body of the fabric will be found still serviceable and capable of much further use, thus 100.

giving to the fabric substantially a double wear quality.

In the manufacture of Fourdrinier wire fabric, it is the common practice to anneal the coppery wires before use to render them soft and more flexible for their travel over the rolls of the machine. But the stretching of such fabrics when in use destroys the annealed property of the coppery wires and tends to make them more stiff and brittle, whereupon they break more easily. By the use of my invention most of this stretching and consequent increase of brittleness in the coppery wires is prevented, and said wires are kept in their soft annealed condition for a long wearing life without breaking.

What I claim is:

1. A paper making wire fabric comprising interwoven warp and weft wires, the weft wires and some of the warp wires being of coppery metal such as brass or bronze and other warp wires of stainless steel interspersed among said coppery warp wires.

2. A paper making wire fabric comprising a plain weave of warp and weft wires, said warp wires being of uniform diameter, the weft wires and some of the warp wires being of coppery metal such as brass or bronze and other warp wires of stainless steel interspersed among said coppery warp wires.

3. A paper making wire fabric comprising interwoven warp and weft wires, the weft wires and some of the warp wires being of coppery metal such as brass or bronze and other warp wires of stainless steel interspersed among said coppery warp wires at regular intervals transversely of the fabric.

4. A paper making wire fabric comprising interwoven warp and weft wires, the weft wires and some of the warp wires being of coppery metal such as brass or bronze and other warp wires of stainless steel interspersed among said coppery warp wires at intervals of approximately $\frac{3}{2}$ of an inch transversely of the fabric.

5. A paper making wire fabric comprising interwoven warp and weft wires forming the body of the fabric, the weft wires and some of the warp wires being of relatively soft metal and the remaining warp wires being of relatively hard metal and of greater tensile strength than the first mentioned warp wires and interspersed at intervals in the body of the fabric among the warps of softer metal.

6. A paper making wire fabric comprising interwoven warp and weft wires forming the body of the fabric, the weft wires and some of the warp wires being of relatively soft metal and the remaining warp wires being of relatively hard metal and of greater tensile strength than the first mentioned warp wires and interspersed at intervals in the body of the fabric among the warps of softer metal, said intervals of dispersion transversely of the body of the fabric being in the order of

one warp wire of harder metal for every seventh warp wire of softer metal.

In testimony whereof I have affixed my signature.

GUY M. PETERSON.
